CLAIM

The ornamental design for a soap dispensing dish brush, as shown and described.

DESCRIPTION

FIG. 1 is a front perspective view of a soap dispensing dish brush, showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

(Continued)

FIG. 7 is a bottom plan view of FIG. 1; and FIG. 8 is a rear perspective view of FIG. 1. The broken lines in the drawings depict portions of the soap dispensing dish brush that form no part of the claimed design.

1 Claim, 5 Drawing Sheets
